CHARLES J. SCHIFFERLE, OF OAKLAND, CALIFORNIA, ASSIGNOR TO HARRY R. STRUTHERS, OF BERKELEY, CALIFORNIA

APPARATUS FOR BURNING GAS

Application filed July 11, 1930. Serial No. 467,172.

My invention relates to an apparatus for preparing a gas for burning, and particularly to such an apparatus for effecting the proper combustion of natural gas.

5 It is among the objects of my invention to provide an apparatus whereby the same burning conditions are secured with the use of natural gas as obtain in the burning of artificial or producer gas.

10 Further objects of my invention include the provision of an apparatus for preparing natural gas for burning which permits combustion to take place within the range of most efficient burning, and with a flame 15 which is readily localized and concentrated.

The invention possesses numerous other objects and features of advantage, some of which, with the foregoing, will be set forth in the following description of my invention.

20 It is to be understood that I do not limit myself to this disclosure of species of my invention, as I may adopt variant embodiments thereof within the scope of the claims.

Referring to the drawings:

25 Figure 1 is a plan view showing a gas burning apparatus embodying my invention used in conjunction with a standard artificial gas burner.

Figure 2 is a similar view showing a modification of my invention; portions of the expansion chamber are broken away to disclose the construction.

30 Figure 3 is a side view, partly in section and partly in elevation, showing an expansion and heater chamber used in conjunction with a standard artificial gas burner for stoves, and illustrates another embodiment of my invention.

Figure 4 is a vertical sectional view showing an expansion and heater chamber formed integral with a furnace door and used in conjunction with a standard burner; this illustration being another modification of my invention; and

45 Figure 5 is a front elevation of the furnace door shown in Figure 4.

In many localities, and particularly on the Pacific coast in the United States, the artificial or producer gas which has been in common use is being replaced with natural gas.

However, since the ignition temperature of natural gas is higher than that of artificial gas, and the heat value of natural gas is substantially twice that of an equivalent amount of artificial gas under the same conditions, 55 any attempts made to burn the natural gas in the standard types of burners which had given efficient results with artificial gas met with serious difficulties.

Chief among these difficulties was due to 60 the fact that, in order to secure substantially the same flame temperature as obtained with the artificial gas, the gas orifice of the burner had to be reduced approximately one-half in size. This led to almost endless trouble, because the small burner orifice continually became clogged with accumulations of foreign matter carried by the flowing gas.

Another difficulty presented itself in consequence of the higher ignition temperature 70 of the natural gas; and this factor, together with the inability of the burners to supply sufficient air to the gas, lead to incomplete combustion.

Still another difficulty arose because the 75 heat value of the natural gas approximated 1100 B. t. u. per cubic foot. Since the upper limit for efficient burning is around 700 B. t. u. per cubic foot, the combustion of the natural gas was highly inefficient.

The broad object of my invention is to provide an apparatus for overcoming these difficulties, and at the same time make it possible to utilize the burners which had been used in conjunction with the artificial gas.

In terms of broad inclusion, the apparatus embodying my invention includes a gas burner, which may be a standard type of burner designed for use with artificial gas. Means are provided for supplying a gas to the burner, and means are provided for expanding the gas prior to its introduction into the burner. This expansion increases the volume and reduces the density of the gas, and it is preferred to increase the volume until the heat value per cubic foot has been reduced to accord with the best practice for efficient burning; viz., below 700 B. t. u. per cubic foot. It is also preferred to heat the gas, prefer-

ably simultaneously with the expansion, to maintain the gas pressure.

In greater detail, the apparatus embodying my invention includes the use of a simple standard type burner 2 provided with the air intake ports 3 and a gas nozzle or orifice 4. Where artificial or producer gas has been used, and is replaced by natural gas, this burner may conveniently be the one previously used in conjunction with the artificial gas. 5 In the form of my invention shown in Figure 1, a gas supply means, or pipe 6, is directly connected to the burner; the gas flow in the supply pipe being controlled by a suitable valve 7.

10 In an attempt to burn natural gas in a simple burner of this sort, by feeding the gas directly to the burner, very poor and inefficient results obtain due to the high ignition temperature and heat value of the natural gas. To overcome this, means are provided for expanding the gas prior to its introduction into the burner. This may conveniently be effected by arranging the supply pipe 6 so that a 15 portion of it is heated by the burner flame.

By heating the gas prior to its introduction into the burner, the gas is caused to expand. This expansion increases the volume and reduces the density of gas. As a result 20 of the increase in volume, the heat value per cubic foot is reduced to within the range of most efficient burner; viz., below 700 B. t. u. per cubic foot. Furthermore, the decrease in density permits air to readily mix with the 25 gas as it discharges in the burner, and sufficient amounts of the air are entrained to permit a complete burning of the gas.

Not only is complete combustion effected, 30 but also, due to the rapid intermixture of gas and air, immediate ignition is brought about. Under these conditions, the flame is readily localized and concentrated, insuring a burning zone which precludes the escape of unburned portions of the gas to such areas 35 where the mixture and temperature conditions interfere with ignition and combustion.

It may be preferable to increase the volume 40 of the gas without materially changing its pressure. To accomplish this, an assembly similar to that shown in Figure 2 may be used. In this case, an annular expansion chamber 8, surrounding the burner 2 and interposed in the supply pipe 6, is provided. As the gas, under a given pressure, enters the chamber 8 45 it expands. This expansion increases the volume and reduces the density, but also operates to reduce the gas pressure. However, the gas in the chamber is heated simultaneously with its expansion, due to the position 50 of the burner 2. As a result of this heating, the pressure of the expanded gas is increased until it approaches the original value.

Figure 3 shows another embodiment of 55 my invention used in combination with a standard type of stove burner 9; and this

burner may conveniently be one previously used in conjunction with artificial gas. A tubular expansion chamber 11 is arranged adjacent the burner 9, so that portions of it are heated by the burner flame.

70 A gas supply pipe 12, connected to a gas main 13 through a suitable valve 14, is sealed in one end of the tube 11 and projects into the expansion chamber. The pipe 12 is positioned to discharge into the expansion chamber adjacent its heated portions, so that the gas will be simultaneously heated and expanded. The expanded gases are conveyed to the burner 9 by a suitable duct 16 leading from the expansion chamber and opening 75 into the burner. The tube 11 slopes downwardly slightly towards its heated portions, and any condensation of the gas in the expansion chamber tends to run down to a point 80 where it will be evaporated.

85 Another embodiment of my invention is shown in Figures 4 and 5. This arrangement is particularly advantageous in furnaces. A hollow door 17, providing an expansion chamber, is mounted on the side of a fire box 18 with suitable hinges 19. The door is provided with a central aperture 21, having an ordinary burner 2 projecting therethrough. A duct 22 is mounted on the outside of the 90 door, and connects the expansion chamber of the door 17 with the burner 2.

95 Means are provided for introducing a gas into the expansion chamber of the door. A gas supply pipe 23 is positioned in axial alignment with the door hinges 19, and is provided with a curved portion 24 opening 100 into the expansion chamber. A control valve 26 is inserted in the supply pipe 23, and a rotary coupling 27 is provided so that the door 17 may pivot on its hinges.

105 The apparatus embodying my invention has many applications, but it is particularly useful in localities where artificial or producer gas is being replaced by natural gas, because the new gas can be made to burn efficiently and economically in the previously used burners. The same burning conditions may be approached as had been obtained in the use of artificial gas, without having to 110 reduce the gas discharge orifice in the burner. A flame is provided which is readily localized and concentrated, and immediate ignition followed by complete combustion is insured.

115 I claim:

120 1. In an apparatus for burning gas, a burner, an expansion chamber adjacent the burner and arranged so that portions of it are heated by the burner flame, a gas supply pipe projecting into the expansion chamber and positioned to discharge at a point adjacent its heated portions, and a duct leading from the chamber and opening into the burner.

125 2. In an apparatus for burning gas, a burner, an expansion chamber comprising a 130

closed tube arranged so that its forward end projects into the burner flame, a gas supply pipe sealed in the rear end of said tube and projecting into the tube to discharge at a point adjacent its heated end, and a duct leading from the rear end of the tube and opening into the burner.

5 3. In an apparatus for burning gas, a burner, an expansion chamber adjacent the burner and arranged so that portions of it are heated by the burner flame, a gas supply pipe 10 opening into the expansion chamber and positioned to discharge at a point adjacent its heated portions, and a duct leading from the 15 chamber and opening into the burner.

In testimony whereof, I have hereunto set my hand.

CHARLES J. SCHIFFERLE.
